UNITED STATES PATENT OFFICE.

CLIFTON D. PETTIS, OF NEW YORK, N. Y.

BRAKE SHOE.

Application filed June 12, 1925. Serial No. 36,617.

The present invention relates broadly to brake shoes, and more particularly to so called filled or composition shoes of the character ordinarily utilized for railway 5 rolling stock.

It has heretofore been proposed in the art to which the present invention relates to construct brake shoes having a central cavity or recess filled with metal or composition different from that constituting the remainder 10 of the brake shoe body, for the purpose of controlling the wear of the shoe and also obtaining the desired coefficient of friction. The bodies of such brake shoes have been constructed of various forms either of steel, 15 ductile shells or cast bodies and the like.

The present invention has for one of its objects the provision of an improved shoe of the filled or composition type, and more particularly the type having a cast metal shell. Heretofore, considerable difficulty has been experienced in the manufacture of such shoes in endeavoring to obtain the necessary strength of the shell with the required size 20 of opening or recess for the filling or composition. With the present invention it is possible to obtain both the requisite strength and dimensions or proportions of the various parts.

30 In the accompanying drawings there are shown for purposes of illustration only certain preferred embodiments of the present invention, it being understood that the drawings do not define the limits of my invention as changes in the construction and operation disclosed therein may be made without departing either from the spirit of the invention or the scope of my broader claims.

In the drawings:

40 Figure 1 is a side elevational view of one form of brake shoe embodying the present invention;

Figure 2 is a top plan view of the construction illustrated in Figure 1;

45 Figure 3 is a transverse sectional view on the line III—III of Figure 2;

Figure 4 is a detail elevational view on an enlarged scale illustrating a portion of the side and end of the metal reinforcing shell;

50 Figure 5 is a view similar to Figure 4 showing one entire end and a portion of the sides of the reinforcing shell; and

55 Figures 6 and 7 are views corresponding respectively to Figures 4 and 5, but illustrat-

ing another embodiment of the present invention.

In carrying out the present invention, there may be utilized a mold of any desired construction adapted to produce a box-shaped shell S having depending side and end walls 2 and a top wall 3. Preferably the construction of the mold will be such as to form side walls or end walls, or both, having inner surfaces 4 which converge 60 downwardly and inwardly whereby there is provided a central opening or recess within the cast shell of gradually decreasing cross sectional area toward the face of the brake shoe. 70

Adapted to cooperate with the cast shell S is a reinforcing shell 5 which may be of steel and of such shape and configuration as to meet the requirements of the particular cast shell being produced. In Figures 1 to 75 5 of the drawings the reinforcing shell is indicated as comprising a back 6 which is substantially imperforate throughout the main body thereof to form the major portion of the exterior of the back of a finished 80 brake shoe. At its central portion the reinforcing shell carries a central lug 7 having outwardly projecting lugs 8 formed thereon for securing the central lug in position. At its ends the reinforcing shell is 85 preferably provided with cut away portions 9 which provide for the formation of the usual end lugs 10 of the brake shoe. At an intermediate portion the reinforcing shell may be formed with a pouring opening 11 90 through which molten metal may be poured during the casting operation.

The back 6 of the reinforcing shell is also illustrated as having substantially imperforate downturned sides or ends 12, or sides 95 and ends adapted to extend over and protect the upper corners or edges of the brake shoe, and these sides carry downwardly and inwardly projecting reticulated portions 13 on the sides, or both the sides and ends. As 100 illustrated more particularly in Figures 4 and 5, the construction of the reticulated portions is such as to provide triangularly shaped openings 14 continuously surrounded by metal whereby during the casting operation the reinforcing shell will become firmly imbedded in or interlocked with the casting. While the specific construction of the reticulated portions is relatively immaterial, I 105 have found that the particular arrangement 110

herein illustrated forms an effective interlock with the molten metal enabling the use of a cast shell in which the amount of metal may be reduced to a minimum. Due to the 5 direction of extension of the reticulated portions, the cast shell is effectively reinforced thereby enabling the cast shell to be made comparatively thinner. It will be noted that the reinforcing is not only effective throughout substantially the entire back, but also at all points where the cast shell is of changing 10 thickness or direction of extension, thereby preventing fracturing of the cast shell where it is ordinarily most susceptible to injury.

15 After the reinforced cast shell has been formed, it may be filled with a suitable composition filling F of any desired nature. This may be metal of different characteristics, or may be a composition of asphalt, 20 iron borings and the like as heretofore proposed in the art. The tapered wall or walls of the central opening effectively engage the composition filling for holding it in place against any possibility of loosening.

25 In Figures 6 and 7 there is illustrated a slightly modified form of the reinforcing shell in which the back 6' and the flanged sides and ends 12' are indicated as being of greater thickness than the reticulated downwardly and inwardly inclined portions 13'. Also, this reinforcing shell is shown as being free from reticulated reinforcing portions at the ends thereof, this being merely for purposes of illustration, it being understood that 30 the reticulations may extend continuously therearound, as before described, if such a construction is desirable.

The advantages of the present invention 40 arise from the provision of a cast metal shell having reinforcing means imbedded therein for strengthening the same, thereby enabling the cast shell to be constructed of the required dimensions for the reception of a composition filling as desired.

45 Further advantages arise from the construction of a filled brake shoe having the shell constructed of reinforced cast metal.

Still other advantages arise from the provision of a cast shell having protected upper 50 edges or corners, and having reinforcing means at points naturally subjected to fracture by reason of changes in direction of extension or cross section.

I claim:

55 1. In a brake shoe, a cast metal shell formed with a recess for the reception of filling material, and reinforcing means for said shell covering substantially the entire back thereof and of greater width and 60 length than the width and length of said recess whereby the cast metal body forming the back of the recess is continuously reinforced, substantially as described.

65 2. In a brake shoe, a cast metal shell formed with a recess for the reception of

filling material, said shell being of box-like contour, and reinforcing means for the back and upper edges of said shell including the upper portion of the side edges thereof effective for reinforcing said shell where it undergoes a change of direction and contour, substantially as described. 70

3. In a brake shoe, a cast metal shell of box-like contour, and reinforcing means entirely exteriorly of the shell for the points of 75 the shell at which it undergoes a change of contour, substantially as described.

4. In a brake shoe, a cast metal shell, reinforcing means therefor, said reinforcing means constituting the main portion of the 80 exterior of the back of said shoe, and a filling within said shell, said reinforcing means being effective in a given plane throughout an area greater than the area of the filling in a plane parallel to said first-mentioned 85 plane.

5. In a brake shoe, a cast metal shell having a recess therein, reinforcing means for said shell, said reinforcing means constituting a substantial portion of the back of said 90 shell and at least an exposed portion of the sides thereof, and a filling within said shell, substantially as described.

6. In a brake shoe, a cast metal shell, reinforcing means therefor, said reinforcing means enclosing a substantial portion of the back of said shoe and at least a portion of the sides and ends thereof, and a filling within said shell, substantially as described. 95

7. In a brake shoe, a cast metal shell, reinforcing means therefor, said reinforcing means having substantially solid portions constituting a substantial portion of the back of said shoe and at least a portion of the sides and ends thereof, and also having 100 reticulated portions, and a filling within said shell, substantially as described. 105

8. In a brake shoe, a cast metal shell, and reinforcing means therefor forming the outside back portion and the adjacent upper 110 side edges of the shoe, said reinforcing means having reticulated portions inturned into the shell, substantially as described.

9. In a brake shoe, a cast metal shell and reinforcing means therefor, said reinforcing means comprising a main body portion forming the outside back portion and adjacent upper side edges of the shoe and having reticulated sides and ends inturned 115 into the shell, substantially as described. 120

10. In a brake shoe, a cast metal shell having a filling receiving recess therein, reinforcing means therefor, said reinforcing means comprising a back and sides, different portions of said means being of different 125 thickness, and a filling within said shell, substantially as described.

11. In a brake shoe, a cast metal shell, and reinforcing means therefor, said reinforcing means comprising a main substan- 130

- tially solid body portion having reticulated portions, substantially as described.
12. In a brake shoe, a cast metal box-like shell, and a reenforcing shell enclosing the back and a portion of the sides thereof, substantially as described.
13. In a brake shoe, a cast metal box-like shell, and a reenforcing shell enclosing the back and a portion of the sides thereof, said reenforcing shell having inturned edge portions embedded in the cast metal shell, substantially as described.
- 10 14. In a brake shoe, a cast metal box-like shell, and a portion of the sides thereof, said reenforcing shell having inturned edge portions embedded in the cast metal shell, substantially as described.
15. In a brake shoe, a cast metal box-like shell providing longitudinal upper edges exteriorly thereof, and reenforcing means embracing said edges, substantially as described.

In testimony whereof I have hereunto set my hand.

CLIFTON D. PETTIS.
